UNITED STATES PATENT OFFICE

2,596,587

STEAM-LIFTING TRAP FOR STEAM-CIRCULATING SYSTEMS

Frederick Stanley Morton, Enfield, England, assignor to Thermomatic (Engineers) Limited, Enfield, England, a British company

Application December 22, 1948, Serial No. 66,657
In Great Britain January 1, 1948

10 Claims. (Cl. 137—103)

1

This invention relates to steam-circulating systems for central heating and the like purposes.

In such systems it is usual to provide means for draining condensed water from the system and returning it to the boiler. This invention is concerned with the type of apparatus in which the condensate drains into a chamber containing a float which controls a valve device for admitting live steam to the sump when it is full so as to force the collected condensate back to the boiler, the valve device being thrown over to cut off the steam and connect the sump to atmosphere as soon as it is emptied, and remaining in this position until the sump is again full of condensate. In such an apparatus, the pipe by which the condensate drains into the sump and the pipe by which the condensate is returned from the sump to the boiler are provided with non-return valves which prevent the condensate from being forced back into the steam-circulating system when the sump is under steam pressure, and prevent water from being forced into the sump from the boiler when the sump is under atmospheric pressure.

In the improvement according to the present invention, the float controlled valve device comprises a pair of simple or compound valves, which control, respectively, a steam inlet and an atmospheric vent, and both of which valves are operated by a common sliding member disposed horizontally and provided with inclined faces which are engaged by corresponding inclined faces of a boss on a rod extending upwards from a float within a sump. The co-operation of these mutually engaging inclined faces causes the valve member to be displaced endwise as the float rises or falls, and the arrangement is such that when the float reaches the top of its travel, the steam inlet is opened and the atmospheric vent closed, and when the float descends to its lowest position, the steam inlet is closed and the atmospheric vent opened, the action being positive in both directions.

It is further desirable to ensure that the steam valve does not open until the chamber is full, and, when once opened, does not close again until the chamber is empty.

This is accomplished, according to a feature of this invention, by providing a spring-loaded device for retaining the float in its highest and lowest positions, the springs of which device are strong enough to retain the float in its highest position except when the chamber is substantially empty, and in its lowest position except when the chamber is substantially full, i. e. the

2

springs will only yield and release the float when subjected to the full weight of the float and elements supported by it or when the float is fully submerged and its buoyancy is a maximum.

5 With this arrangement, the total travel of the float may be small relatively to the total rise and fall of the water level in the chamber.

In one preferred embodiment, the spring-loaded device takes the form of a ball catch comprising two or more spring-loaded balls engageable with one or other of two grooves in an upward extension of the float rod.

In another preferred embodiment, the spring-loaded device is of the toggle type and comprises horizontally movable spring-loaded plungers connected to an upward extension of the float rod by toggle links.

Since in either preferred embodiment, i. e. that comprising the ball catch and that having a toggle device, the spring restraint on the float and parts supported thereby is the same in both the highest and lowest positions of these parts, it follows that the net upward force exerted on the spring-loaded device when the float chamber is substantially full must be equal to the downward force on the spring-loaded device when the float chamber is substantially empty. This can be achieved by appropriately weighting the float in relation to its buoyancy.

30 According to a feature of the invention, the valves respectively controlling the steam inlet and atmospheric vent are compound valves each comprising a needle-type valve and a piston-type valve operative in series, the piston-type valves being so arranged that substantially the full stroke in the appropriate direction of the common sliding member is required to open one or the other of them completely.

The accompanying drawings illustrate, by way of example, several embodiments of the invention. In the drawings:

Figure 1 is a diagram of a steam-heating system embodying an apparatus for returning condensate to the boiler according to the present invention;

Figure 2 is an elevation of the apparatus partly sectioned;

Figure 3 is a central vertical section of the upper part of the apparatus;

Figure 4 is a section on the line 4—4 of Figure 3;

Figure 5 is an elevation, partly in central section, of a modified form of the uppermost part 55 of the apparatus; and

3

Figure 6 is a part plan, part section, on the line 6—6 of Figure 5.

Referring to Figure 1, a boiler 10 delivers live steam to an uptake pipe 11 which feeds radiators or the like 13 through valves 12, the condensate being returned by a pipe 14, in which are two non-return valves 15, 16. Between the two non-return valves, a branch pipe 17 communicates with the bottom of the chamber of the apparatus 18 to the top of which are connected a steam pipe 19 communicating with pipe 11, and an atmospheric vent 20.

The apparatus 18 (see Figure 2) comprises a cylindrical float-chamber 21, into the bottom of which pipe 17 opens, and which encloses a float 22. The top of the chamber 21 is closed by a flanged valve-body 23 which communicates with the steam pipe 19 and with the atmospheric vent 20. One face of the valve-body is provided with a removable inspection cover 63 (see also Figure 4).

On the top of the float 22 (see Figure 3) is mounted a socket 24 having vertically slotted openings 25 accommodating a bolt 26, which passes through a block 27, into which is screwed the lower end of a vertical rod 28. The latter extends upwardly through a guide 29 screwed into the base 30 of the valve-body 23. Openings 30^a in the base 30 (see Figure 4) provide free communication between the interior of the float chamber 21 and the interior of the valve body. The upper end of rod 28 is screwed into a boss 31 having inclined faces 31^a which engage, with easy clearance, opposed mating faces 32^a of an opening in a transverse valve-member 32 terminating at both ends in needles 33 which enter self-seating thimbles 34 having conical ends. Each thimble 34 is loosely secured to a needle 33 at the free or outer end thereof and, hence, is movable toward and from the adjacent valve seat in accordance with corresponding movements of the needles. As the thimbles 34 are loosely secured to the needles 33, said thimbles can partake of limited rocking movements on the ends of said needles, whereby said thimbles are free to align themselves with their associated valve seats as the needles are moved to closed position on said associated valve seats. The latter seat on seating faces 35 formed in valve-seatings 36 which are screwed into valve-pockets 37. If the seating faces 35 wear out of true, the thimbles 34 accommodate themselves to them and maintain a good seal. The valve-pockets 37 are internally-threaded into the valve-body 23 and have screwed necks 38, 39, which receive, respectively, the pipes 19, 20 (see Figure 2). The valve-pockets 37 are also provided with screw plugs 40, removal of which gives access to the seatings 36 for inspection, adjustment or removal. The inner ends of the valve-pockets 37 extend into the valve-body and are provided with ports 41 which afford communication between the bores of the valve-pockets and the interior of the valve-body 23, but can be obstructed by the sliding valve member 32. The valve-member 32 slides in the bores of the valve-pockets 37 in which it is a good sliding fit.

When the float 22 rises, the inclined faces of block 31 move the member 32 to the left, as seen in Figure 3, bringing the left-hand thimble 34 onto its seating and closing the left-hand set of ports 41, the right-hand thimble being freed to leave its seating and the right-hand ports 41 being uncovered. This admits steam from pipe 19 to the float-chamber 21. When the float falls,

4

the member 32 is moved to the right closing the right-hand needle valve 34, 35 and right-hand ports 41 and opening the left-hand needle valve 34, 35 and left-hand ports 41 as shown in Figures 3 and 4. This cuts off the steam from pipe 19 and opens the float-chamber to atmosphere through the vent 20.

It will be seen that both the steam admission valve and the atmospheric vent valve comprise needle valves 34, 35 and piston valves 32, 41 arranged in series. The piston valve components ensure that full admission of steam or full release to atmosphere cannot take place until the valve member 32 is thrown over to its full extent in one direction or the other. The needle valves 34, 35 provide an efficient seal when the combined valve is closed.

It will also be noticed that the components of the steam admission valve including the valve pocket 37, seating 36, thimble 34 and screw plug 40 are identically similar to the corresponding components of the atmospheric vent valve and are interchangeable therewith. Also, the two needles 33 of the valve member 32 are identically similar.

The rising and falling of the float is controlled by a ball catch device comprising a casting 44 secured to the top of the valve body 23 and having two standards 44^a, 44^b, respectively, into which are screwed housings 45 enclosing balls 46 and springs 47 retained by screwed plugs 48, by means of which the spring tension may be adjusted and which are protected by screwed caps 49. The balls 46 are pressed inwards horizontally by the springs to engage one or other of a pair of circumferential grooves 50^a, 50^b of a cap 50 which is screwed onto the upper end of an extension rod 42 whose lower end is screwed into the block 31 in alignment with the rod 28. The rod 42 slides in a guide 43 screwed into the base of the bracket 44 and into the top of the valve body 23. The cap 50 is provided with an extension rod 51 which is guided in a bridge piece 52 secured to the top of the standards 44^a and 44^b. The extension rod 42 is provided with conical seating collars 61, 62 which seat on conical faces at the top and bottom of the guide 43 when the float 22 and the parts supported thereby are in their lowest and highest positions, respectively.

The tension of the springs 47 are adjusted so that when the balls 46 are engaged with the lower groove 50^a of the cap 50, the springs 47 will not yield and allow the float 22 to fall unless the float-chamber 21 is empty of liquid, i.e. so long as there is any buoyancy to relieve the weight suspended on the ball catch the latter will not yield and allow the float to drop. Similarly, when the balls 46 are engaged with the upper groove 50^b of the cap 50, the springs 47 will not yield and allow the float 22 to rise until the float-chamber 21 is full enough completely to submerge the float and the float experiences the maximum buoyancy effect of the contained liquid. It will be evident that the critical vertical load on the cap 50 at which the ball catch will yield must be the same whether applied upwardly or downwardly, and consequently the float 22 must be so weighted in relation to its buoyancy that the total weight suspended on the cap 50 when the float chamber is empty is equal to the buoyancy of the float when completely submerged less the weight of the float and the parts supported by it.

The apparatus above described operates as follows: Referring to Figures 1 and 2, condensate

draining down the pipe 14 passes the non-return valve 15 and enters the bottom of the float-chamber 21 of the apparatus 18 through the branch pipe 17. When sufficient condensate has accumulated in the float-chamber 21 to submerge the float 22 completely, the latter rises from the position shown in Figure 3 sufficiently to engage the balls 46 with the lower groove 50^a of the cap 50. In rising through this distance, the inclined faces of the block 31 throw the transverse sliding valve member 32 over from right to left, as seen in Figure 3. This allows the thimble 34 of the steam valve on the right of Figure 3 to leave its seating 35 and uncovers the ports 41 of the steam valve, at the same time closing the ports 41 of the atmospheric vent valve on the left of Figure 3 and bringing the thimble 34 of this valve onto its seating. In this movement, the ports 41 of the steam valve are not fully uncovered until the needle valve 34, 35 controlling the atmospheric vent is closed. This movement of the parts admits live steam from the pipe 19 through the steam valve into the valve body and thence through the openings 30^a into the float-chamber, the liquid contents of which are returned through the branch 17 and the non-return valve 16 back into the boiler. The opening of the steam valve communicating with the pipe 19 equalises the pressures above and below the contents of the float chamber, and the return of the contents of the float-chamber to the boiler is effected by gravity due to the head provided by mounting the apparatus 18 at a level above that of the boiler.

As soon as the float-chamber is emptied, the float 22 is released by the ball catch 46 and falls again, throwing the valve member 32 over to the right, the parts being returned to the position shown in Figure 3, thus closing the steam inlet valve and opening the atmospheric vent valve and allowing the excess steam to escape through the ports 41 and valve 34, 35 to the atmospheric vent 20, the pressure in the float-chamber being again reduced to atmospheric.

This cycle continues to repeat itself, the ball catch 46 ensuring that the valve member 32 is thrown over smartly in alternate directions when the float chamber becomes full and empty, respectively.

The ball catch 46 may be replaced by the modification illustrated in Figures 5 and 6 in which the extension rod 42 carries a collar 53 secured in fixed position on extension rod 42 by nuts 54, the collar 53 being connected by hinged toggle links 55 with plungers 56 sliding horizontally in housings 57 secured to the standards 44^a and 44^b, respectively, and enclosing springs 58 retained by adjustable screw plugs 59, the latter being protected by screw caps 60. This arrangement gives a positive upward or downward force on the float and parts supported thereby in all intermediate positions of the float between the highest and lowest position. This is advantageous, especially when the apparatus is required to operate in a high-pressure steam system carrying a working pressure of 150 lbs. or more. In such a system, the condensate on entering the float chamber, which is at atmospheric pressure, releases large quantities of steam owing to the drop of pressure, and if, as normally occurs, the condensate enters the float chamber faster than this steam can be released, the condensate level may rise sufficiently to initiate the lifting of the float and then fall again owing to release of steam before the float has risen fully. With the ball-catch type of float-control there is then no extraneous force

70
75

tending to complete the rising of the float, which may stick half-way between its extreme position and be held there by the balls engaging the collar 50 frictionally between the grooves 50^a, 50^b. The steam valve is thus held half-open giving partial admission of steam to the float-chamber sufficient to prevent the entry of further condensate but insufficient to empty the chamber of condensate. The positive action of the toggle-mechanism effectively prevents this type of failure. However, with more moderate steam pressures, the ball catch is found to be effective and reliable and the apparatus is not subject to the type of failure discussed above.

I claim:

1. An apparatus for collecting condensate from a steam circulating system and returning the same to the boiler comprising a chamber having spaced, relatively opposite inlet and outlet openings at the upper portion thereof, said inlet opening adapted for connection to a source of steam and said outlet opening adapted to vent said chamber to atmosphere, said chamber also having a branch pipe at the lower portion thereof communicating with the interior of said chamber, one branch of said pipe adapted for connection with a pipe for conducting the condensate from the system into said chamber, said last named pipe having a non-return valve therein permitting condensate to pass through said one branch and into said chamber, and the other branch of said pipe adapted for connection with a pipe for conducting the condensate from the chamber back to the boiler, said last named pipe having a non-return valve therein permitting the condensate to pass from said chamber back to the boiler; a slid valve member mounted for reciprocation between the spaced, relatively opposite inlet and outlet openings and having valve means on the ends thereof adapted to alternately open and close said inlet and outlet openings; a float within said chamber adapted to rise or descend in accordance with the presence or absence, respectively, of condensate within said chamber; and a member connected to said float and movable therewith in a direction normal to the direction of movement of said valve member, said valve member and the member connected to said float having cooperating, slidably engaging, substantially parallel faces inclined obliquely to a vertical plane perpendicular to the line of movement of said valve member, the direction of inclination of said cooperating faces being such that the valve member is reciprocated in a direction to open the inlet valve and close the outlet valve when the float rises and to close the inlet valve and open the outlet valve when the float descends.

2. An apparatus as defined in claim 1 in which the inlet and outlet openings each include axially disposed and radially disposed openings with the radially disposed openings spaced inwardly with respect to the axially disposed openings, and wherein each end of the valve member includes a needle-type valve adapted to seat on the axially disposed opening adjacent that end of the valve member and a piston-type valve adapted to control the radially-disposed openings adjacent said end of said valve member.

3. An apparatus as defined in claim 1 in which the inlet and outlet openings each include an inwardly-facing valve seat, and wherein each end of said valve member has loosely secured thereto a conically-ended thimble which seats on an adjacent valve seat self-adjustably when said valve

member is moved to valve closing position with respect to said adjacent valve seat.

4. An apparatus as defined in claim 1 in which a spring loaded means engages the member connected to the float and movable therewith for yieldingly retaining the float in its uppermost and lowermost positions, said spring loaded means yielding and permitting the float to rise only when the chamber containing the float is substantially full of condensate, and permitting the float to descend only when the said chamber is substantially empty.

5. An apparatus as defined in claim 1 in which the member connected to the float has upper and lower, spaced, circumferential grooves thereon, and in which a spring loaded ball catch frictionally engages one or the other of said grooves, said catch yieldingly retaining the float in its uppermost and lowermost positions by engagement with said upper or lower grooves, respectively, said catch yielding to disengage the upper groove and permit the float to rise only when the chamber containing the float is substantially full of condensate, and yielding to disengage the lower groove and permit the float to descend only when the said chamber is substantially empty.

6. An apparatus as defined in claim 1 in which the member connected to the float and movable therewith has a collar thereon connected by hinged toggle links to spring-loaded plungers, said links and spring-loaded plungers exerting positive upward or downward forces in all intermediate positions of the float between its uppermost and lowermost positions.

7. An apparatus as defined in claim 1 in which spring loaded means engages the member connected to the float and movable therewith for yieldingly retaining the float in its uppermost and lowermost positions, said spring loaded means yielding and permitting the float to rise only when the chamber containing the float is substantially full of condensate, and permitting the float to descend only when the said chamber is substantially empty, and in which the weight of the float and parts supported thereby is adjusted with relation to the buoyancy of the float so that the net upward force exerted on the spring loaded means when the chamber is substantially full of condensate is equal to the downward force exerted on the spring loaded means when the float chamber is substantially empty.

8. An apparatus for collecting condensate from a steam circulating system and returning the same to the boiler comprising a chamber having spaced, relatively opposite inlet and outlet openings at the upper portion thereof, said inlet opening adapted for connection to a source of steam and said outlet opening adapted to vent said chamber to atmosphere, said chamber also having a branch pipe at the lower portion thereof communicating with the interior of said chamber, one branch of said pipe adapted for connection with a pipe for conducting the condensate from the system into said chamber, said last named pipe having a non-return valve therein permitting condensate to pass through said one branch and into said chamber, and the other branch of said pipe adapted for connection with a pipe for conducting the condensate from the chamber back to the boiler, said last named pipe having a non-return valve therein permitting the condensate to pass from said chamber back to the boiler; a slideable valve member mounted for reciprocation between the spaced, relatively op-

posite inlet and outlet openings and having valve means on the ends thereof adapted to alternately open and close said inlet and outlet openings, said valve member being provided intermediate the ends thereof with an opening defined by walls including spaced, substantially parallel end walls inclined obliquely to a vertical plane perpendicular to the direction of movement of said valve member; a float within said chamber adapted to rise or descend in accordance with the presence or absence, respectively, of condensate within said chamber; and a member connected to said float and movable therewith, said member passing through the opening in said valve member and having spaced, parallel walls mating and slidably engaging the inclined end walls of the opening in the valve member, the direction of inclination of said spaced end walls and said mating walls being such that the valve member is reciprocated in a direction to open the inlet valve and close the outlet valve when the float rises and to close the inlet valve and open the outlet valve when the float descends.

9. An apparatus for collecting condensate from a steam circulating system and returning the same to the boiler comprising a vertically disposed tubular chamber; a valve body secured to the top of said chamber and enclosing a space communicating with the interior of said chamber; two valve pockets secured, respectively, to one side and to the other side of said valve body and extending thereinto in communication with said space and at relatively opposite locations, one of said pockets adapted for connection to a source of steam and the other to vent said chamber to atmosphere; a branch pipe at the lower portion of said chamber and communicating with the interior of said chamber, one branch of said pipe adapted for connection with a pipe for conducting the condensate from the system into said chamber and having a non-return valve therein, and the other branch of said pipe adapted for connection with a pipe for conducting the condensate from the chamber back to the boiler and having a non-return valve therein; a slideable valve member including a needle-type valve on each end thereof and mounted within said valve body for reciprocation between the relatively opposite valve pockets; each of said valve pockets including a valve seating portion having coaxially extending bores with an axially and inwardly directed valve seat intermediate said bores, the inner end of each valve seating extending into the space within the valve body and having radially extending ports through the wall thereof communicating with said space, the bore within said inner end of each valve member having a sliding fit with and providing a sliding support for one end of the slideable valve member, said radially extending ports cooperating with the end portions of the slideable valve member to constitute piston-type valve means, and the valve seat intermediate the ends of each pair of coaxial bores cooperating with the needle-type valve at the ends of said slideable valve member to constitute needle-type valve means; a float within said tubular chamber adapted to rise or descend in accordance with the presence or absence, respectively, of condensate within said chamber; and a member connected to said float and movable therewith for moving said slideable valve member in a direction to open the needle-type valve means and the piston-type valve means in the valve pocket adapted for connection to a source of steam and to close the needle-type valve means and the pis-

ton type valve means in the opposite valve pocket upon rise of said float within said tubular chamber, and for moving said slideable valve member in the opposite direction to open the needle-type and the piston-type valve means in the valve pocket adapted to vent said tubular chamber to atmosphere and to close said needle-type and piston-type valve means in the opposite valve pocket upon descent of said float within said tubular chamber.

10. An apparatus as defined in claim 9 in which a separate sleeve member is adjustably screwed into the outer end of each pair of the coaxial bores in each valve pocket, and in which the inner end portion of each sleeve member includes the valve seat intermediate the ends of each pair of coaxial bores.
